Primary Examiner — Paula Greene*(74) Attorney, Agent, or Firm* — Craig A. Deutsch**CLAIM**

The ornamental design for a hearing device tether acoustic decoupling section as shown and described.

DESCRIPTION

FIG. 1 is a front perspective view for a hearing device tether acoustic decoupling section showing my new design;

FIG. 2 is a front view; the back view is a mirror image thereof;

FIG. 3 is a left view thereof;

FIG. 4 is a right view thereof; and,

FIG. 5 is a top view; the bottom view is a mirror image thereof.

Broken lines form no part of the claimed design, and any shading is provided to illustrate contour only and is not an indication of texture, gloss, etc.
